CASKET AND HANDLE THEREFOR
Bernard H. Koppen, 509 E. Lincoln St., Belvidere, Ill.
Filed Nov. 23, 1962, Ser. No. 239,490
7 Claims. (Cl. 27—2)

This invention relates to caskets and particularly to carrying handles for caskets.

An important object of this invention is to provide a casket and carrying handle therefor in which the handle is so arranged as to simulate a decorative ornament, when the handle is not in use.

A more particular object of this invention is to provide a carrying handle for a casket wherein the handle, when not in use, can be moved to a position in which the handle simulates a medallion and pendent to thereby avoid the functional and utilitarian appearance normally incident to casket handles.

Yet another object of this invention is to provide a carrying handle for a casket which can be used without modification on either side or on the ends of a casket to reduce the number of different parts which must be made and stocked.

Still another object of this invention is to provide a carrying handle for a casket which can be selectively moved to either of two relatively opposite carrying positions for use in carrying the casket in either direction.

Yet another object of this invention is to provide a carrying handle for a casket which is of simple construction, and which is strong and durable to withstand the heavy loads and forces imposed on the handle during use, and which is yet graceful and decorative in appearance.

These, together with other objects and advantages of this invention will be more readily appreciated as the same becomes better understood by reference to the following detailed description when taken in connection with the accompanying drawings wherein:

FIG. 1 is a side view of a casket having the carrying handle of the present invention applied thereto;

FIG. 2 is a plan view of the handle assembly and illustrating different moved positions of the handle;

FIG. 3 is a fragmentary sectional view through the handle assembly;

FIG. 4 is a fragmentary transverse sectional view, taken on the plane 4—4 of FIG. 3; and

FIG. 5 is a fragmentary transverse sectional view, taken on the plane 5—5 of FIG. 3.

Reference is now made more specifically to FIG. 1 wherein there is illustrated a casket, of conventional construction, and which employs spaced side walls 10, end walls 11, a bottom wall 12 and a cover 13. The caskets are commonly designed and ornamented to provide a decorative appearance. However, the carrying handles heretofore provided on caskets have been such that their utilitarian purpose has been quite apparent and have detracted from the overall ornamental appearance of the casket. A number of bearers are used in carrying the casket and it is necessary to enable gripping of the casket at a number of points along the length thereof. A common type of carrying handle presently being provided on caskets is in the form of an elongated bar which extends lengthwise of the sides of the casket. In accordance with the present invention, a plurality of individual carrying handle assemblies 15 are provided, and which handle assemblies are so constructed and designed as to minimize or avoid the appearance of being functional or utilitarian, when the handles are not in use. As shown in FIG. 1, a plurality of handle assemblies, herein shown three in number, are provided on each of the sides 10 of the casket and, preferably, like handle assemblies are provided on the ends 11 for use in carrying the casket and also

for lowering the casket into the grave. In accordance with the present invention, the handle assemblies are so arranged that they can be used, without modification, on either side or on the ends of the casket, and can, moreover, be used when carrying the casket in any direction.

The handle assemblies 15 include a mounting plate 21, preferably shaped in the form of a decorative medallion, and which mounting plate is conveniently formed with opening 22 for receiving fasteners 23 to attach the mounting plates to the sides or ends of the casket. The mounting plate is advantageously made concavo-convex as shown in FIG. 3, to provide adequate strength while minimizing the amount and weight of the material required to form the same. A reentrant sleeve 25 is formed on the mounting plate 21 and extends rearwardly thereof to define a socket 26. As will be seen from FIG. 3, the peripheral rim portion 27 of the mounting plate terminates in a flat rear face 28 adapted to rest against the side or end of the casket, when the handle assembly is attached thereto, and which flat face is disposed rearwardly of the end of the socket 25. The socket 25 also includes an end wall 29 at the rear end thereof and an opening 31 in the end wall. The carrying handle 32 has a generally L-shaped configuration and includes a hand grip portion 33 and a pintle portion 34 which extends generally perpendicular to the hand grip portion adjacent one end thereof. The pintle portion 34 is rotatably supported in the socket 26 and is retained against axial withdrawal by means of a screw 35 which is threaded into a tapped opening 36 in the handle. The screw 35 is advantageously provided with a collar 37 under the head and which collar is slightly thicker than the rear wall 29 of the sleeve to enable tightening and locking of the screw against the end of the pintle portion 34 without causing binding between the handle and the end wall.

The handle 32 is arranged to normally extend downwardly, when not in use, and to simulate a pendant attached to the medallion shaped mounting plate 21, as best shown in FIGS. 1 and 2. In order to enable carrying of the casket in either direction, the handle is arranged to be swung either to the left or to the right as viewed in FIG. 2 from the pendant position shown in solid lines, to a generally horizontal carrying position, shown in phantom in FIGS. 1 and 2. A stop means is provided on the pintle portion 34 and on the sleeve 25 for stopping the handle in either of its carrying positions.

As shown in FIGS. 3—5, the stop means includes a generally crescent shaped lug 41 formed on the interior of the sleeve 25 adjacent its rear end, and which lug defines opposed stop faces 42 and 43. The pintle portion 34 is formed with a reduced diameter inner end portion 34a and a generally crescent shaped lug 44 which defines opposed stop faces 45 and 46. The stop faces 42, 45 and 43, 46 are arranged such that, when the hand grip portion 33 extends downwardly as shown in FIGS. 2 and 3, the stop faces are angularly spaced apart approximately 90° to enable swinging movement of the handle through substantially 90° in either direction from the downwardly extending position to either of two oppositely extending generally horizontal positions for carrying. Thus, when the handle is swung to the left as shown at 33', the stop face 45 on the pintle portion will engage the stop face 42 on the sleeve and, similarly, when the handle is swung in the opposite direction to the position shown at 33", the stop face 46 will engage stop face 43.

Thus, the handle can be swung from a pendant position to either of two relatively opposite horizontal carrying positions so that the handle can be arranged to extend horizontal and project rearwardly relative to the path of travel, when the casket is carried in either direction. Moreover, this arrangement also enables use of the same handle

assembly on either side of the casket, or on the ends, without requiring modification in the construction. As will be seen from FIG. 3, the hand grip portion is spaced laterally from the mounting plate 21 and from the wall of the casket when the handle is mounted thereon, to provide clearance around the hand grip portion for the reception of the hand of the bearer. In order to enhance the clearance, without loss in strength or rigidity, the mounting plate 21 is advantageously formed with oblong shape as best shown in FIG. 2, and is mounted on the casket with the major axis extending vertically. Thus, when the hand grip portion is in its pendant position, it parallels the major axis of the oblong mounting plate, and when the handle is in either of its generally horizontal carrying positions, it parallels the minor axis of the oblong mounting plate so that the major portion of the hand grip projects beyond the outer edge of the mounting plate. With this arrangement, interference between the hand of the user and the mounting plate, during carrying of the casket is minimized.

I claim:

1. In combination with a casket having opposed sides and ends, at least two independent handle assemblies mounted on each side of the casket intermediate the ends, said handle assemblies each including a mounting plate attached to the side of the casket and a carrying handle individual to each mounting plate, said handles having a generally L-shaped configuration and having a hand-grip portion and a pintle portion extending generally perpendicular to one end of the hand-grip portion, means non-slidably and rotatably mounting the pintle portion of each handle on a respective mounting plate for swinging movement about an axis generally perpendicular to the side of the casket with the hand-grip portion of the handle laterally spaced from the mounting plate and the side of the casket to allow gripping of the handle, said pintle mounting means supporting said handles for swinging movement between a normal downwardly extending position selectively in either direction to first and second relatively opposite horizontal positions for carrying the casket in either direction, and first and second stop means for limiting upward swinging movement of the handle to said first and second horizontal positions.

2. In combination with a casket having opposed side and end walls, at least two independent handle assemblies mounted on each side wall of the casket intermediate its ends and one handle assembly mounted on each end wall, said handle assemblies each including a mounting plate attached to a respective wall of the casket and a carrying handle individual to each mounting plate, said handles having a generally L-shaped configuration and having a hand-grip portion and a pintle portion extending generally perpendicular to one end of the hand-grip portion, means non-slidably and rotatably mounting the pintle portion of each handle on a mounting plate for swinging movement about an axis generally perpendicular to the respective wall with the hand-grip portion of the handle laterally spaced from the mounting plate and wall to allow gripping of the handle, said pintle mounting means supporting said handles for swinging movement between a normal downwardly extending position selectively in either direction to first and second relatively opposite horizontal position for carrying the casket in either direction, and first and second stop means for limiting upward swinging movement of the handle to said first and second horizontal positions.

3. In combination with a casket having opposed sides and ends, at least two independent handle assemblies mounted on each side of the casket intermediate the ends, said handle assemblies each including a mounting plate and a carrying handle individual to each mounting plate,

5 said handles having a generally L-shaped configuration and having a hand grip portion and a pintle portion extending generally perpendicular to one end of the handle portion, said mounting plates having sockets therein disposed generally perpendicular to the side of the casket and rotatably receiving said pintle portions of the handles to support the latter for swinging movement about an axis generally perpendicular to the side of the casket with the hand grip portion laterally spaced from the mounting plate and the side of the casket to allow gripping of the handle, said sockets supporting said handles for swinging movement from a normal position in which the hand grip portion extends downwardly selectively in either direction to first and second relatively opposite horizontal positions, and means on said pintle portions and said sockets retaining the pintle portions in the sockets and defining first and second stops for limiting upward swinging movement of the hand grip portion to said first and second horizontal positions.

20 4. In combination with a casket having spaced sides, a plurality of casket handle assemblies on the sides of the casket, each casket handle assembly comprising a mounting plate, means mounting the plate on the side of the casket, said mounting plate having a socket in one side thereof extending generally perpendicular to the side of the casket, a carrying handle having a generally L-shaped configuration and including a hand grip portion and a pintle portion on one end of the hand grip portion extending generally perpendicular thereto, means non-slidably and rotatably mounting said pintle portion in said socket for turning movement about the axis of the socket and generally perpendicular to the side of the casket, and stop means on said socket and said pintle portion for limiting swinging movement of said hand grip portion through an angle of approximately 180° between first and second relatively opposite horizontal positions for use in carrying the casket in either direction, said hand grip portion being swingable to a third downwardly extending position intermediate said first and second positions to simulate a decorative pendant when the handle assembly is mounted on the casket, and said stop means preventing upward swinging of the hand-grip portion of the respective handle above said horizontal positions.

30 5. The combination of claim 4 wherein said socket has an apertured end wall, said means mounting said pintle portion on said socket including a headed screw extending through said apertured end wall and into said pintle portion.

40 6. The combination of claim 4 wherein said stop means includes a lug on said socket defining first and second angularly spaced stop faces and a lug on said pintle defining third and fourth angularly spaced stop faces respectively engageable with said first and second stop faces when said hand grip portion is in said first and second positions.

50 7. The combination of claim 6 wherein said mounting plate has an oblong shape and said stop faces are arranged so that the hand grip portion substantially parallels the minor transverse axis of the oblong plate when the hand grip portion is in said first and second positions and substantially parallels the major transverse axis of the mounting plate when the hand grip portion is in said third position.
